WILLIAM D. JONES, OF PATILLAS, PORTO RICO.

CABLE-GUIDE FOR SHEAVES AND PULLEYS.

1,087,951.

Specification of Letters Patent. Patented Feb. 24, 1914.

Application filed January 15, 1913. Serial No. 742,253.

To all whom it may concern:

Be it known that I, WILLIAM D. JONES, residing at Patillas, Porto Rico, have invented certain new and useful Improvements in Cable-Guides for Sheaves and Pulleys, of which the following is a specification.

My invention relates to cable guides for sheaves and pulleys, and particularly to a cable guide adapted to be used in connection with that type of dumping car wherein the car dumping mechanism is operated by an air actuated piston controlled by a cable.

In this form of dumping car a cable guide is mounted adjacent to and extends partially around the circumference of the sheave or pulley, and this guide is mounted upon the bolster column. This guide so mounted, is very liable to break or to be bent due principally to the cars running off the track, which occurs very often. When so broken or bent the cable runs off the sheave or pulley losing control of the piston and this either causes the piston head to burst or smashes the cylinder head, thus rendering the dumping mechanism inoperative. To remedy this, it is necessary to remove the old bolster column and put in an entirely new bolster column, even though the column itself is as good as new, the column being useless, however, because of the breaking of the guide. This entails not only an expense, due to the actual cost of the column itself, but also loss of time during which the car is laid up for repairs and the expense of the wages to the repairers.

The main object of my invention is, therefore, to so construct a cable guide for this type of cars that it may be readily removed or replaced in case of breaking without removing or replacing the bolster column and without consequent loss.

A further object is to so construct the guide that not only is it effective as a cable guide *per se* but that it also shall form a washer to take the place of the ordinary washer disposed between the sheave and the cotter pin holding the sheave in place.

A further object is to provide a guide adapted to be placed either on the right or left hand side of a pulley so that one guide may be used for different situations.

A further object is to so construct the

guide that the cotter pin shall positively hold the guide in a set position.

My invention is illustrated in the accompanying drawings, wherein—

Figure 1 is a fragmentary perspective view of a portion of a dumping car and cable sheave showing my invention applied to the sheave. Fig. 2 is a horizontal section taken diametrically across the sheave and showing my attachment applied to the sheave hub. Fig. 3 is a face view of the sheave, a portion of the bolster column and my cable guide. Fig. 4 is a face view of the cable guide detached from the sheave. Fig. 5 is a fragmentary section on the line 5—5 of Fig. 4, showing one of the studs, which are disposed on each side of the cotter pin groove.

Referring to these drawings, it will be seen that I have shown my guide as applied to a cable sheave mounted in connection with a dumping car of the type described, only so much of the car being shown as will illustrate the application of my invention.

Referring to Fig. 1, A designates the bolster column, and B a bracket attached to the bolster column and projecting out therefrom and carrying an arcuate guide C. Projecting from the bolster column is a fixed hub 2 upon which the sheave D is rotatably mounted. This sheave may have any ordinary or desired form. The arcuate cable guide C extends transversely across the face of the pulley but is spaced therefrom and extends longitudinally along a portion of the circumference of the pulley. All of these parts are old and form no part of my invention. The extremity of the hub 2 is transversely pierced for the passage of a cotter pin 3 of the usual form.

My improved guide comprises an annular terminal portion designated 4 which has an opening 5 in its center adapted to fit over the projecting end of the hub 2 and an arm 6 which extends out from the terminal portion, this arm being angularly bent, as at 7, so as to extend across the edge face of the sheave. The extremity of this angular portion 7 being again bent inward, that is, toward the axis of the sheave, as at 8, and extending over the margin of the sheave.

The cable guide may be made, of course, of any suitable material and have any desired

dimensions, but I have found in practice that it is best to make it of steel one sixteenth of an inch in thickness, with the projecting arm 6 thereof about two inches wide and nearly five inches in length.

In order that the guide may be held in proper angular relation to the axis of the pulley, I provide means upon the outside face of the annular portion 4 of the guide which will engage the cotter pin 3 and hold the guide in its proper position. To this end I preferably form the outer face of the annular portion of the guide with a recess or groove 9 which extends diametrically across the annular portion of the guide and which is adapted to receive the two legs of the cotter pin.

In order to permit the guide to be used on one or the other side of a pulley and further adapt the guide to be used with pulleys in any desired situation I preferably provide two of the cotter pin engaging grooves 9. The second of these grooves is designated 9^a and differs in its angular position from the groove 9.

In order to prevent any movement of the guide from its proper angular relation to the cotter pin I preferably provide studs 10 which are disposed on each side of the grooves 9 and 9^a. These studs, preferably, are somewhat conical in form and may either be cast integral with the guide in case the latter is cast, or may be separate from the material of the guide and attached thereto in any suitable manner, as by forming each stud with a reduced shank extending through and mounted upon the inner face of the guide. These studs are so disposed that they will engage with the cotter pin in case a strain comes upon the guide, and will prevent any rotation of the guide upon the hub.

It will be noted that in the guide, as described, the annular portion 4 forms a washer disposed between the inner face of the cotter pin and the adjacent or outer face of the sheave.

I have found in practice that these cable guides are exceedingly effective for the purpose described and that they positively hold the cable E in place and prevent it running off the sheave.

Having described my invention what is claimed as new is.

1. A cable guide for sheaves comprising an annular portion adapted to fit over the hub of the sheave, and an arm projecting from the annular portion and extending at right angles at its outer end, the annular portion of the guide being formed with a pair of diametrically extending cotter pin grooves, the grooves being set at an angle to

each other to permit the annular portion to be disposed on the right hand or left hand side of a sheave.

65

2. A cable guide for sheaves having an annular portion adapted to fit over the hub of the sheave and formed with an outwardly projecting member adapted to extend over said sheave and having two diametrically disposed cotter pin grooves, the grooves crossing each other whereby the guide may be reversed in position with relation to the sheave.

3. The combination with a hub, a sheave mounted thereon, and means for holding the sheave in place upon the hub, of a cable guide comprising a plate formed with an annular portion at one end adapted to engage over the hub and against the sheave, said plate extending outwardly beyond the sheave and being then bent across the periphery of the sheave, and means for holding the guide in a fixed angular position with relation to the hub.

75

4. The combination with a hub, a sheave mounted upon the hub, and a cotter pin passing through the hub, of a cable guide comprising a plate having an annular portion at one end adapted to fit over the hub, said annular portion having a diametrically disposed groove upon its outer face adapted to partially embrace the cotter pin, said plate extending outward to the circumference of the sheave and being then angularly bent across the face of the sheave.

80

5. The combination with a hub, a sheave mounted thereon, and a cotter pin extending therethrough of a cable guide comprising a plate having an opening at one end adapted to fit over the hub and having a plurality of grooves in its face, said grooves extending diametrically across the opening, and being adapted to partially embrace the cotter pin, the outer extremity of the plate being angularly bent.

90

6. The combination with a hub, a sheave mounted upon the hub, and a cotter pin, of a cable guide comprising a plate having an opening at its end adapted to fit over the hub, this end of the plate being formed with a plurality of grooves extending diametrically across the opening and adapted each to partially embrace the cotter pin, the face of the plate being provided with spaced lugs disposed one on each side of each groove, and said plate at its extremity being angularly bent over the face of the sheave.

105

In testimony whereof I affix my signature in presence of two witnesses.
